[57] ABSTRACT

An internal combustion engine and vehicle drive assembly including two separate engines connected together with an accessory drive output through an intermediate housing supporting the engines in a connected relationship. The intermediate housing supports and aligns the engines while providing for the mounting of a coupling output shaft underneath and lateral to connected crankshafts of the separate engines. A splined coupling member connecting the respective crankshafts within the intermediate housing includes means for providing the drive output driving engine accessories which can be mounted upon the intermediate housing. This arrangement accommodates the use of a single water pump and oil pump in conjunction with a single oil sump to respectively cool and lubricate the connected engines.

**CONNECTING AND ACCESSORY DRIVE MEANS
FOR SEPARATE INTERNAL COMBUSTION
ENGINES**

This invention relates to means for coupling two separate internal combustion engines and for providing a drive output therefrom and more specifically to a structure for connecting two separate rotary engines while also providing for an accessory drive means whereby the accessories may be mounted upon an intermediate housing supporting the engines and enclosing the connecting means.

Mounting of internal combustion engines within vehicle engine compartments continuously poses a problem with respect to the mounting of engine driven accessories. With the advent of air conditioning and additional engine driven components for the comfort of vehicle occupants, the problem of mounting engine accessories within an engine compartment have become magnified. Additionally, with regard specifically to rotary combustion engines, use of more than two rotors severely complicates the provision of necessary crankshaft supporting bearings including the required sealing and assembly thereof.

The present invention makes use of an intermediate housing to align and support two separate internal combustion engines in a connected relationship. In preferred form, the intermediate housing is formed including a flange aligning with an end plate flange of the respective engines for connecting the intermediate housing to the respective engines thereby securing the engines together. The separate internal combustion engines are completely assembled with sufficient bolts through their end plate flange to retain them in assembled relationship. The end plate flanges accommodate positioning dowel pins and additional machine screws for rigidly securing the engines to the intermediate housing in aligned relationship. Of course, it is obvious that the aligning dowel pins can either be secured to the engine flange or to the intermediate housing flange so as to insure proper alignment between the mating members. Use of dowel pins to align the intermediate housing with the engines has particular application to rotary internal combustion engines. The connected engines, of course, can be of either single or multiple rotor design. In the assembly of rotary internal combustion engines, it is common practice to use dowel pins to insure proper alignment of the rotor housing and the respective end housings. With respect to the structure of the present invention, these commonly used dowel pins can be also utilized to align the intermediate housings with their respective engines and they can be lengthened to accomplish this result if necessary. In the assembly of the rotary housing and the respective end housings, relatively long through bolts are inserted through aligned apertures in the respective housing members and the bolts are torqued a predetermined degree to rigidly secure the members together. Advantage of this method of assembly is taken in the securing of the intermediate housing to the engines. A predetermined number of the through bolts are torqued to secure the engines in assembled relationship and a remaining predetermined number of apertures through the aligned housing members are left vacant for receipt of a somewhat longer through bolt which rotatably engages an aligned aperture in the flange of the intermediate housing. Clearance apertures in the intermediate

housing flange are provided to receive the extending ends of the engine assembly bolts. Therefore, with this arrangement an assembled engine can be aligned with the intermediate housing by virtue of the extended dowel pins being received in precisely located apertures in the intermediate housing flange and the remaining longer through bolts being inserted and torqued to rigidly secure the assembly together.

The intermediate housing is essentially in the form of a box with open sides defined by the securing flanges. The respective engine crankshafts extend into the intermediate housing and include male splined surfaces on their terminating ends. A splined coupling member is positioned over the crankshaft ends and provides a driving connection therebetween by virtue of the mating splines. An accessory drive sprocket is secured to or is integral with the external surface of the splined coupling and in this manner provides a driving connection to accessories mounted within the intermediate box as well as any accessories that may be mounted on the exterior surface thereof. The splined coupling driving sprocket can engage a cog belt or a chain to drive the engine accessories. Since the chain or cog belt provides a positive drive relationship engagement with driven engine distributor sprockets, a positive driving relationship between the distributors and the engine crankshafts is provided so that a timed relationship is maintained therebetween.

In an assembled relationship, the intermediate housing positively aligns and supports the respective engines. One outer end of the connected crankshafts is coupled through a sprocket, driving a chain to a laterally disposed transmission assembly having an output shaft extending parallel to the longitudinal axis of the connected crankshafts. The transmission output shaft is connected to a conventional bevel gear box which in turn is drivingly connected to a coupling shaft rotatably mounted in the intermediate housing below the connected crankshafts. The coupling shaft is rotatably supported in a position such that its longitudinal axis is substantially normal to the longitudinal axis of the connected crankshafts. The other end of the coupler shaft connects with a bevel gear drive output to vehicle wheel axles. The other outer end of the connected crankshafts can have accessory drive pulleys mounted thereon such as, for example, a pulley driving power steering and air conditioning systems along with a second pulley driving a water pump to supply coolant to the interconnected engines.

By connecting separate internal combustion engines via an intermediate housing, the present invention insures positive support and alignment of the connected engines while simultaneously providing a simple and economical means of mounting and driving engine accessories. Also the utilization of a transmission having an output shaft parallel to the interconnected crankshafts allows a coupler shaft to be rotatably mounted in the intermediate housing to supply power from the transmission to driven vehicle axles. A further advantageous result of the present invention resides in the fact that a single oil sump can be used in conjunction with a single oil pump to provide lubrication to both engines. Likewise a single water pump can be used to supply coolant to both of the engines, one of the coolant lines being optionally mounted in the oil sump thereby cooling the oil while supplying coolant to one of the engines.

Accordingly, a prime object of this invention is the provision of a new and improved means of interconnecting separate internal combustion engines.

Another object of this invention is the provision of a crankshaft coupling member having means thereon for driving engine accessories.

A further object of this invention is the provision of an intermediate housing member rigidly connected to two separate internal combustion engines so as to structurally support them in a connected relationship.

A still further object of this invention is the provision of an intermediate housing member rigidly supporting connected internal combustion engines while also including means to positively position them in an aligned relationship.

Another object of this invention is the provision of an intermediate housing member connecting separate internal combustion engines together in aligned relationship while simultaneously enclosing a crankshaft connecting member having accessory drive means thereon which is drivingly connected to a plurality of engine accessories mounted upon the intermediate housing.

A further object of this invention is the provision of connected internal combustion engines having their crankshafts connected together via a splined coupling and being rigidly supported in an aligned relationship by means of an interconnected member, one outer end of the connected crankshafts being utilized to drive adjacent accessories, the other outer end of the connected crankshafts being drivingly connected to a transmission assembly having an output shaft with its axis parallel to that of the connected crankshafts and being drivingly engaged with a coupling output shaft rotatably mounted in the intermediate housing below the connected crankshafts for drivingly connecting the transmission output shaft with driven vehicle axles.

Another object of this invention is the provision of separate internal combustion engines being rigidly supported by an intermediate housing member with their crankshafts drivingly connected by means of a splined coupling member within the intermediate housing, a single oil pump and sump assembly being provided to supply lubricant to both of the connected engines and a single water pump being utilized to supply coolant to both of the connected engines.

The novel features which I believe to be characteristic of my invention are set forth with particularity in the appended claims. My invention itself, however, both as to its organization and method of operation, may be best understood by reference to the following description taken in connection with the accompanying drawings in which:

FIG. 1 is a top plan view illustrating two separate internal combustion engines connected together via an intermediate housing as provided in accordance with the present invention.

FIG. 2 is a bottom plan view illustrating utilization of a single oil sump and water pump to supply lubricant and coolant to the separate interconnected engines.

FIG. 3 is a fragment of a magnified top plan view illustrating means of interconnecting the separate engine crankshafts of my invention.

FIG. 4 is a sectional view taken on line 4-4 of FIG. 3 illustrating the accessory drive arrangement of my invention.

FIG. 5 is an end plan view of the intermediate housing of my invention.

FIG. 6 is a perspective view of the splined coupling of my invention utilized to interconnect the separate engine crankshafts.

FIG. 7 is a perspective view of a modified splined coupling of my invention.

The intermediate housing structure utilized to connect separate internal combustion engines and the accessory drive arrangement from a member connecting the separate crankshafts of the present invention can be used in conjunction with internal combustion engines of any type, such structure being specifically shown in an arrangement connecting rotary engines primarily for purposes of description only.

Referring to FIG. 1, which is a top view of an engine assembly in accordance with my invention, two separate rotary engines 10 and 12 are shown connected together by a predetermined number of through bolts 13 threadably engaging or otherwise secured to an intermediate housing 14. The engine crankshafts are connected together within housing 14 as will later be described. The outer end 16 of the crankshaft in engine 10 supports an accessory drive pulley assembly 18 that can be connected by a belt 20 to drive various accessories such as a vehicle air conditioning compressor, a power steering pump and a water pump, an air conditioning compressor 22 only being shown in FIG. 1. A starter 23 engages a conventional ring gear 25.

The outer end 24 of the crankshaft in engine 12 connects with a belt or chain drive unit 26 of a conventional transmission unit 28 including an output shaft having a longitudinal axis 30 parallel to a longitudinal axis 32 of the connected engine crankshafts. The transmission output shaft connects with a coupler shaft assembly 34, shown in FIG. 3, which has a longitudinal axis 36 substantially perpendicular to the transmission shaft axis 30 and is connected thereto through a diagrammatically illustrated conventional bevel gear box 38. The shaft 34 is a structural part of the present invention and is connected to vehicle drive axles 40 and 42 via an axle gear box 44, as shown in FIG. 1. The intermediate housing 14 can be configured to have any number of engine accessories mounted thereon, engine compartment space being the major limiting factor. Clusters of accessories 46 and 47 are shown mounted on the housing 14 in FIG. 1, this mounting arrangement being later described in detail.

Referring now to FIG. 2, which is a bottom view of the engine assembly, a sump 48 is utilized to collect transmission fluid for supply to the conventional transmission assembly 28. The rotary engine 10 has a single oil sump 50, common to both engines and containing a single oil pump, not shown. The sump 50 supplies oil to the oil pump for lubricating both engines and receives returning oil from engine 12 through a conduit 52. A relatively small collector 54 is attached to the underneath side of engine 12 for collecting oil to be returned through the conduit 52 to oil sump 50. A conventional transmission fluid cooler assembly 56 is attached underneath engine 12. A water pump 58 is secured to engine 10 and is driven by the outer end 16 of the connected crankshafts. The water pump 58 supplies coolant to engine 10 through a conduit 60 and simultaneously supplies coolant to engine 12 through a conduit 62 which is disposed within oil sump 50 for simultaneously cooling the oil.

Referring to FIG. 3, the outer end 16 of crankshaft 64 within engine 10 has a splined portion 66 slidably receiving a like splined portion 68 on the pulley assembly 18. The pulley assembly 18 can include a first pulley section 70 integral with an engine counterbalance weight 71 and providing a driving connection to accessories mounted adjacent the end of engine 10 and can further include a second pulley section 72 likewise suitable for use in driving accessories mounted adjacent the end of engine 10. The water pump assembly 58 is mounted near the crankshaft end 16 and can be driven by the pulley assembly 18 pressurizing coolant for supply to both of the engines 10 and 12.

The crankshaft 64 terminates in a splined portion 74, at its other end 76, which drivingly engages a bracket 78 secured to the crankshaft end 76 by means of a securing block 80 and a machine bolt 82. An engine counter-balance weight 79 is integral with the bracket 78. The bracket 78 also has a splined portion 84 on an external surface thereof.

Engine 12 includes a crankshaft 86 having an end 88 formed with a splined portion 90 on the exterior surface thereof. A driving sleeve member 92, having internal splines 94, is slidably positioned upon the spline portion 90 of crankshaft 86 providing a driving connection therebetween. The sleeve 92 is secured to end 88 of crankshaft 86 by a machine bolt 96 and includes an external splined portion 98. The engines 10 and 12 are secured together via the aforementioned intermediate housing 14 which will be specifically described later in detail. The housing 14 specifically aligns engines 10 and 12 relative to one another so that the longitudinal axis of the crankshafts 64 and 86 are precisely aligned on the longitudinal axis 32 as shown in FIG. 3. The crankshafts 64 and 86 slidably receive a splined coupling member 100 which contains internal splined portions 102 and 104 respectively engaging splines 84 and 98 of bracket 78 and sleeve 92. It is obvious that these splined surfaces may be reversed on the respective members to obtain the driving connection. The coupling member 100 includes an integral sprocket 106 which drivingly engages a cog type belt 108 for providing a driving connection to a plurality of engine accessories.

The aforementioned coupler shaft assembly 34 is positioned within intermediate housing 14 for rotation underneath and laterally to the previously described longitudinal axis 32 of the connected crankshafts 64 and 86. The coupler shaft assembly 34 includes a stub shaft 110 rigidly supporting a bevel gear 112 providing a power transmitting connection to the conventional bevel gear box 38. The coupler shaft assembly 34 also includes a second stub shaft 114 which is likewise rotatably supported within the intermediate housing 14 to provide a drive connection through a bevel gear 116 to the axle gear box 44. An intermediate coupling shaft 118 is disposed between the stub shafts 110, 114 and is drivingly connected to them via a splined sleeve 120 at each end thereof which engages male splined surfaces 122 on the stub shafts and male splined surfaces 124 on the stub shaft ends. The coupler shaft assembly 34 can readily be disassembled by removing a spring locking ring 126 from a groove 128 in the male splined surfaces 122 of the respective stub shafts. Removal of the spring ring 126 provides for sliding movement of the sleeves 120 upon the splined surfaces releasing the intermediate coupling shaft 118 from the assembly.

With reference to FIG. 4, the cog belt 108 engages external teeth 128 on the sprocket 106 which, in preferred form, is integral with the splined coupling member 100. In this manner, the aligned connected crankshafts drive the belt 108 which in turn provides power to a plurality of accessories. Specifically, the belt 108 leaves the right hand side of sprocket 106, passes around an idler sprocket 130, and moves upwardly to drivingly engage a distributor sprocket 132. The belt 108 passes the distributor 132 out of intermediate housing 14 and engages a driven pulley 134 of an alternator assembly 136 from which it moves underneath and into positive engagement with a second distributor drive pulley 138. The belt 108 then continues to drivingly engage an air injection recirculating pump pulley 140 from which it passes downwardly within the intermediate housing 14 for engagement with an oil pump driving pulley 142. The teeth 144 on the cog belt 108 engage mating teeth 129 on the driving sprocket of the splined coupling member 100 as well as mating teeth 146 on the respective distributor drive sprockets 132 and 138. The engagement of these mating teeth between the cog belt 108 and the distributor drive sprockets provide a positive driving relationship between the engine crankshafts 64 and 86 via the splined coupling 100 and teeth 129 on sprocket 106 so that the distributors can be positively timed to provide proper engine operation. In other words, the firing of the engine's ignition system can be precisely timed through the cog belt in relation to rotation of the pistons within the rotary engines 10 and 12. More specifically, with respect to connecting two twin rotor engines together, applicant has determined that it is desirable to position the plane of the crankshaft throws of one of the engines 10 or 12 90° out of phase with the plane of the throw of the crankshaft of the other engine 10 or 12 when connecting them together via the splined coupling member 100. This 90° out of phase relationship provides for a combined smoother performance of the two connected dual rotor engines. The out of phase relationship would be optimized for other engine combinations. It would be at an optimum angle providing minimum engine cranking torque requirements by phasing the rotors so that the compression strokes do not occur simultaneously. Also the engine phasing angle lowers the torque in the drive train by evening the firing pulses so that minimum drive strength and consequently drive component sizes can be used. Another factor in determining the optimum angle is that of engine noise level. All of these factors would be considered in arriving at the phase angle between the engines for a particular installation.

With reference now to FIG. 5, an end view of the intermediate housing 14 is shown. The housing 14 is configured to present a flange 150 conforming to the flanges of the engine housings 152 utilized to secure the rotary engines 10 and 12 in assembled relationship. As shown in FIG. 3 with respect to engine 10, the through bolts 13 utilized to secure the end housings 152 and 154 to a rotor housing 156 can be utilized to secure the separate assembled engines to the respective end flanges 150 of intermediate housing 14, the identical arrangement being used to secure engine 12 to housing 14 but not being shown. The end flanges 150 of intermediate housing 14 are drilled to include a predetermined number of larger diameter holes 158 receiving bolts head 13' of through bolts 13 in the assembled en-

gines so that flange 150 directly engages a similar flange on the engines 10 and 12. A predetermined number of remaining smaller bolt holes 160 are provided in the flange 150 for snugly receiving slightly longer through bolts 13 for securing the engine to the intermediate housing 14. As shown in FIG. 3, the bolt heads 13' engage the inner surface of flange 150 when nut 13'' is torqued down to secure the engines 10 and 12 against respective flanges 150 of housing 14. The engagement between the engine flanges and flanges 150 structurally adds to the rigidity of the assembly.

Alignment of the respective engines in connected relationship is, of course, essential to insure precise connection of the aligned crankshafts. Precise engine alignment with the intermediate housing 14 is accomplished by making use of dowel pins in apertures 162 and 164 which are also used to align the end housing members 152 and 154 relative to rotor housing 156. Of course, it is not necessary to utilize these presently used dowel pins to obtain the desired alignment. Dowel pins can be positioned at any convenient location in the engaging end flanges between respective assembled engines and intermediate housing 14 to accomplish such alignment.

By making use of the engine assembly through bolts to secure the intermediate housing to the engine end housings, a rigid fastening of these members can readily be accomplished by specifically positioning the bolts to provide the most beneficial structural results. As previously mentioned, the through bolts required to engage the intermediate housing flange must necessarily be of a longer length than those normally used to maintain the engine in assembled relationship. By prelocating the securing holes 160 in the flange 150 of intermediate housing 14 it is only necessary to remove the standard through bolts from the assembled engine and insert the longer bolts 13 in order to rigidly secure the engine to the intermediate housing. The intermediate housing has an accessory supporting bracket 166 welded thereon. The bracket can be of any form suitable for supporting a plurality of accessories. As shown, the bracket 166 includes a first distributor supporting slot 168, an alternator supporting arm 170 and a second distributor supporting slot 172.

FIG. 6 is a perspective view of the splined coupling member 100 and best illustrates the sprocket 106 comprising teeth 129 on the exterior thereof. The splined coupling member as previously mentioned includes internal splines 102 and 104 for providing a driving engagement with the respective male spline surfaces 84 and 98 on bracket 78 and sleeve 92 providing a positive driving connection between the aligned crankshafts 64 and 86. The splined coupling member 100 can include timing marks 174 and 176 which can be located in predetermined positions for timing the ignition of the respective engines 10 and 12. Also marks 178 and 180 can be provided on the coupling 100 for alignment with mating marks on the crankshafts to establish the desired phase angle therebetween. The splined coupling member 100 can further include an engine balance weight 182 so as to provide smoother operation of the connected engines.

A modified form of the splined sleeve coupling 100 is shown in FIG. 7. In this form, two accessory drive sprockets 106' and 106'' are positioned adjacent each end of the sleeve for engaging respective accessory cog drive belts 108 and 108' as shown in FIG. 1. With this

arrangement a cluster of accessories 46 can be mounted on the right side of housing 14 for engine 10 and a second cluster of accessories 47 can be mounted on the left side of housing 14 for engine 12.

5 While I have shown and described a particular embodiment of my invention it will, of course, be understood that various modifications and alternative constructions thereof may be made without departing from the true spirit and scope of my invention and that I intend by the appended claims to cover all such modifications and alternative constructions as fall within the true spirit and scope of my invention.

I claim:

1. An internal combustion engine assembly including 15 two separate engines drivingly connected with their respective crankshafts in axial alignment comprising: a coupling member positioned intermediate the aligned crankshafts and providing a driving connection therebetween; accessory driving means on the exterior surface of said coupling member; a plurality of engine accessories mounted with their respective driven members coplanar with said accessory driving means; means providing a driving connection between said accessory drive means and said driven means; an intermediate housing member secured to the respective engine housings fastening them together and enclosing said crankshaft coupling member; means extending between said engines and said intermediate housing maintaining the engines in alignment; and an outer end of one engine crankshaft being drivingly connected with a vehicle transmission assembly providing an output from the engine assembly.

2. A rotary internal combustion engine assembly including two separate rotary engine assemblies drivingly connected with their respective crankshafts in axial alignment comprising: a coupling member positioned intermediate the aligned crankshafts and providing a driving connection therebetween; said crankshafts being positioned to place the engines out of phase for smoother operation when said coupling member is connected to said crankshafts; accessory belt driving means on the exterior surface of said coupling member; a plurality of engine accessories mounted with their respective driven pulleys coplanar with said accessory belt driving means; an endless driving belt placed upon said belt driving means and said driven pulleys following a circuitous path circumferentially around said crankshaft coupling member; an intermediate housing member secured to the respective two rotor engine housings fastening them together and enclosing said crankshaft coupling member; means extending between said engines and said intermediate housing maintaining the engines in alignment; said intermediate housing including apertures permitting the ingress and egress of said belt for driving the accessories mounted exteriorly of said intermediate housing; and an outer end of one engine crankshaft being drivingly connected with a vehicle transmission assembly providing an output from the rotary engine assembly.

3. A four rotor internal combustion engine and vehicle drive assembly comprising in combination: two separate two rotor engines; an intermediate housing member connecting said engines together and supporting them with their crankshafts in axial alignment; a plurality of dowel pins extending between said intermediate housing and said engines maintaining them in alignment; a splined coupling member disposed within said

intermediate housing drivingly connecting said crankshafts in a 90° out of phase relationship; a drive pulley integral with said coupling member on its outer periphery; a plurality of engine accessories mounted with their respective driven pulleys coplanar with said drive pulley; an endless belt placed upon said drive pulley and said plurality of driven pulleys providing a driving connection therebetween; said intermediate housing including apertures permitting the ingress and egress of said belt for driving the accessories mounted exteriorly of said housing; a second driving pulley assembly mounted on an outer end of one of said coupled crankshafts; at least one engine accessory mounted with its driven pulley coplanar with said second driving pulley; an endless belt disposed upon said pulleys providing a driving connection therebetween; a third driving means mounted on the other outer end of said connected crankshafts; a transmission assembly; means drivingly connecting said transmission assembly with said crankshaft third driving means; a coupling shaft rotatably mounted in said intermediate housing substantially normal to said crankshafts and said transmission output shaft; a coupling shaft rotatably mounted in said intermediate housing below said crankshafts; a beveled gear assembly drivingly connecting said transmission output shaft with said coupling shaft; a beveled gear assembly drivingly connecting said coupling shaft with vehicle axles providing a driving connection therebetween; an oil sump being provided in connection with one of said two rotor engines and being in fluid connection with both of said rotor engines for supplying lubricant thereto; a gear type oil pump in fluid communication with said oil sump providing positive lubricant circulation to said engines; and a water pump having two outlets being driven from said second driving pulley mounted on the outer end of one of said coupled crankshafts supplying coolant directly to one of said two rotor engines while the coolant to the second two rotor engine passes through the oil sump.

4. A four rotor internal combustion engine and vehicle drive assembly as described in claim 3 wherein a common oil sump is located under one engine only and is connected to supply lubricant to both engines.

5. A four rotor internal combustion engine and vehicle drive assembly as described in claim 3 wherein a water pump is driven from one end of the connected crankshafts and supplies coolant to both engines, the flow to one engine being direct while the flow to the second engine is through the oil sump.

6. A four rotor internal combustion engine and vehicle drive assembly as described in claim 3 wherein said drive pulley is located adjacent one end of said coupling member for driving the accessories of one engine and a second drive pulley is located adjacent the other end of said coupling member for driving the accessories of the other connected engine.

7. A four rotor internal combustion engine and vehicle drive assembly as described in claim 3 wherein said drive pulley integral with said splined coupling member and said accessory driven pulleys are sprockets and said endless belt is a cog belt providing a driving connection therebetween.

8. A four rotor internal combustion engine and vehicle drive assembly comprising in combination: two separate two rotor engines; an intermediate housing member connecting said engines together in a back-to-front relationship and supporting them with their crankshafts in axial alignment; a plurality of dowel pins extending between said intermediate housing and said engines maintaining them in alignment; a splined coupling member disposed within said intermediate housing drivingly connecting said crankshafts in a 90° out of phase relationship; a cog drive pulley integral with said coupling member on its outer periphery; a plurality of engine accessories mounted on the exterior of said intermediate housing with their respective driven pulleys coplanar with said cog drive pulley; engine balance weights secured to said coupling member; an endless cog belt disposed upon said drive pulley and said plurality of driven pulleys providing a driving connection therebetween in a circuitous path about said coupling

member; said intermediate housing including apertures permitting the ingress and egress of said belt for driving the accessories mounted on said intermediate housing; a second driving pulley mounted on an outer end of one of said coupled crankshafts; a plurality of engine accessories mounted on one of said two rotor engines with their driven pulleys coplanar with said second driving pulley; an endless belt disposed upon said pulleys providing a driving connection therebetween; a third driving means mounted on the other outer end of said connected crankshafts; a transmission assembly including an output shaft parallel to said coupled crankshafts; means drivingly connecting said transmission assembly with said crankshaft third driving means; a coupling shaft rotatably mounted in said intermediate housing substantially normal to said crankshafts and said transmission output shaft; a coupling shaft rotatably mounted in said intermediate housing below said crankshafts; a beveled gear assembly drivingly connecting said transmission output shaft with said coupling shaft; a beveled gear assembly drivingly connecting said coupling shaft with vehicle axles providing a driving connection therebetween; an oil sump being provided in connection with one of said two rotor engines and being in fluid connection with both of said rotor engines for supplying lubricant thereto; a gear type oil pump in fluid communication with said oil sump providing positive lubricant circulation to said engines; and a water pump having two outlets being driven from said second driving pulley mounted on the outer end of one of said coupled crankshafts supplying coolant directly to one of said two rotor engines while the coolant to the second two rotor engine passes through the oil sump.

9. A rotary internal combustion engine assembly including two separate rotary engine assemblies drivingly connected with their respective crankshafts in axial alignment comprising: a coupling member positioned intermediate the aligned crankshafts and providing a driving connection therebetween; said crankshafts being positioned to place the engines out of phase for smoother operation when said coupling member is connected to said crankshafts; accessory belt driving means on the exterior surface of said coupling member; a plurality of engine accessories mounted with their respective driven pulleys coplanar with said accessory belt driving means; an endless driving belt placed upon said belt driving means and said driven pulleys following a circuitous path circumferentially around said crankshaft coupling member; an intermediate housing member secured to the respective rotary engine housings fastening them together and enclosing said crankshaft coupling member; means extending between said engines and said intermediate housing maintaining the engines in alignment; oppositely facing flanges on said intermediate housing engaging respective mating flanges on the engine housings for fastening them together; said intermediate housing flanges containing apertures of sufficient size receiving through bolts maintaining the engines assembled, the apertures providing for mating engagement of said respective flanges; said intermediate housing flanges also containing apertures receiving slightly lengthened through bolts extending through each engine housing and respective intermediate housing flanges for securing the engines to said intermediate housing; said intermediate housing including apertures permitting the ingress and egress of said belt for driving the accessories mounted exteriorly of said intermediate housing; and an outer end of one engine crankshaft being drivingly connected with a vehicle transmission assembly providing an output from the rotary engine assembly.
